UNITED STATES PATENT OFFICE.

EDWARD ALARIC FALCONER, OF MAIDENHEAD, ENGLAND.

LOCK AND INDICATOR FOR HOLDING AND LOCATING KEYS, TOOLS, AND OTHER PORTABLE ARTICLES.

Application filed March 12, 1925, Serial No. 15,066, and in Great Britain March 12, 1924.

Where a key, special tool or other article is kept in a special place for the common use of a number of persons, for example, in an office, store, warehouse, workshop, factory, hotel or other place, it frequently happens that much time is lost in searching for such key or article when the same is not in its usual place, as there is no means of indicating by whom it was last removed.

In the specification of a prior Patent No. 1,472,297, dated Oct. 30, 1923, a device was described which had for its object to provide a lock and indicator for locking articles as described in such a manner that they could not be taken away leaving behind an indication showing which of the persons having access thereto had removed them and such device comprised a lock or holding device called "locator" provided with a retaining catch or catches and a key or plug which was adapted to be held in the "locator" by the aforesaid catch or catches and only capable of being released by the insertion of a particular token or indicator, which after releasing the key or plug and permitting its withdrawal remained in the "locator" until the key was again inserted.

The "locator" key or plug had secured to it the article to be located, for example, a key, bunch of keys, special tool or some other article and each person entitled to use the said article was provided with a token or indicator bearing a number or some other means of identification, so that the article removed could be at once traced by looking at the token or indicator left in the "locator", which token or indicator was exposed through a suitable aperture.

The object of the present invention is to improve the construction of a device, such as above described, for the purpose of simplifying the operative mechanism, to cheapen the general construction, provide a smaller and more compact device for the purpose of enabling it to be used in larger numbers at one place without unduly requiring a large amount of space, to enable the device to be more readily assembled during the manufacture and at the same time to increase its efficiency and security.

Now according to the present invention the casing or cover of the locator is formed with an opening in the front for the insertion of the locator key or plug to which the article to be located is attached, and the

token or indicator employed to release the key or plug, instead of passing through the locator as heretofore is inserted and removed through one and the same slot in the top of the casing, means controlled by the locator key or plug being provided to lock the token or indicator in the casing while the plug or key is withdrawn and spring actuated levers being arranged to engage the key or plug and retain it in the casing when the token is withdrawn, said levers being operated by the token to release the key, and also preferably arranged subsequently to eject the token in an upward direction when same is released by the insertion of the key or plug in the "locator" casing.

The key or plug may be made of cylindrical or any other suitable cross-section with or without wards as required, and is provided with grooves and projections for co-operating with the levers and locking mechanism as hereinafter described.

The invention is hereinafter described with reference to the accompanying drawings in which:—

Figs. 1 and 2 are front and side elevation respectively, of a "locator" constructed according to this invention with the casing or cover removed, but its position indicated by chain lines.

Fig. 3 is a vertical section of the "locator" with the casing or cover in position.

Fig. 4 is a plan projected from Fig. 1.

Figs. 5 and 6 are detail views drawn at right angles to one another, showing one form of the "locator" plug or key.

Fig. 7 is a perspective view on a smaller scale of a complete "locator" including a token or indicator and plug or key.

In the drawings Figs. 1 to 6 are drawn to an enlarged scale for clearness of illustration.

As shown in the drawings a convenient construction of "locator" comprises a stamped sheet metal base or backplate *a* adapted to be fixed to a wall or board in any convenient manner, and a casing or cover *b* fixed to the back plate by integral tongues passed through slots in the plate and bent over at right angles. The said casing or cover is provided at the top with a slot *c* for the insertion or removal of the token or indicator *d* and in the front with a suitable opening *e* for the insertion of the plug or

key f . An aperture g is also provided in the front of the casing for exposing the token or indicator after it has been inserted by the user, or a portion of the indicator 5 may be arranged to project above the casing for exposing an identification number, or the like.

Within the casing b and suitably attached to the base plate a by screws h screwing into 10 distance stays is a carrier plate j for the principal parts of the moving mechanism and said carrier plate is shaped to form guides i for the token or indicator d as it is inserted through the slots c at the top of 15 the casing b . A boss j^2 with guide aperture for the key or plug f is also formed on the plate j at right angles to the token guide. The carrier plate j has mounted upon it a pair of levers k with means such as projections k' on the levers which extend through 20 slots in the boss j^2 into the path of the key or plug f and engage in a groove f' in the said key or plug f to retain the same in locator. In the upper ends of the levers k pins l are fixed which project through a 25 horizontal slot j' in the plate j into the path of the indicator or token d and together with the levers k are forced towards each other by wire springs m . The springs m 30 and levers k are conveniently supported on the lower distance stays as shown.

Upon the insertion of a token or indicator d into the locator the levers k are operated to withdraw the projections k' from the 35 grooves f' and release the key by the said token or indicator pressing against the pins on the upper ends of the levers k and forcing the levers apart in opposition to the action of two springs m .

40 When the levers k have been moved apart sufficiently to release the plug or key f the token or indicator d is engaged by a spring actuated locking device for retaining the token or indicator in the "locator". As 45 shown the locking device consists of a U-shaped member n the arms of which are mounted to slide in openings in the plates a , j , and are arranged to engage the token or indicator and hold it in position after 50 insertion against the action of the levers k . The arms of the U-shaped member n are guided by the openings in the carrier plate j in a position to engage the upper edge of the token or they may engage slots in an- 55 other form of indicator after the said token or indicator has been inserted in the slot. A spring o located vertically behind the case or back plate a is suitably bent at its upper end for positive engagement with the 60 U-shaped member n and tends to maintain the locking member n in the locking position until displaced by the insertion of the key. The displacement of the locking member n from the locking position is effected by an 65 extension f^2 on the end of the key which

passes through an opening p in the plate a and forces back the spring o . The said locking device is itself prevented from operation by means of a gravity or spring controlled safety catch q until the plug or key has been 70 re-inserted in order to prevent misuse by unauthorized persons.

As shown the safety catch q engages over the lower edge of a slot in the spring o and holds the same against displacement until 75 release by the part f^3 of the plug acting on the projection g' of the catch.

As illustrated in Figs. 5 to 7 the key or plug used with the above described construction of "locator" is cylindrical in cross-section but it may be of any other suitable cross-section and is provided with wards as required. In the form of key shown in the drawings a groove f^4 is made longitudinally in the key or plug for the passage of 85 a ward r in the key hole. It will also be seen that the position of the extension f^2 and its aperture may be varied slightly to act as a ward. Means are provided for readily changing the wards by forming the 90 same for example on a removable disc or ring s of the required shape inserted in a recess s' surrounding the key opening of the "locator" when such are desired, such change being useful for preventing the insertion of a key into the "wrong" locator.

Wards or the like devices may also be provided on the token to prevent the use of a plain disc of metal or the insertion of 95 a token into the "wrong" locator.

The "locators" are supplied in single units or in multiples mounted on a suitable base, the multiple unit type being especially useful for keyboards.

The present system of locating keys on a 105 board provided with hooks is most unsatisfactory, since there is no check on those who use them.

Now with a locator keyboard, each key is attached to its respective locator plug, and 110 this locator plug will only fit into its respective locator body, so that No. 1 key must always be returned to No. 1 locator, No. 2 to No. 2 and so on. It will therefore be 115 seen that with the locator keyboard any missing keys can at once be identified, and over and above that it tells who removed them.

I claim—

1. A lock and indicator of the nature 120 specified for holding and locating keys, tools and other portable articles and comprising a casing with apertures in the front and top for the insertion and withdrawal of a key or plug and the insertion and ejection or withdrawal of a token or indicator respectively, and retaining mechanism in the casing co-operating with the key or plug and token or indicator in such manner that the insertion of the token or indicator ef- 125 130

fects the release of the key and retention of the token or indicator while the insertion of the key or plug effects the release of the token or indicator and retention of the key or plug, substantially as described.

2. A lock and indicator according to claim 1, wherein the retaining and release mechanism for the key or plug and token or indicator comprises a pair of spring actuated levers arranged to engage with both the key or plug and the token or indicator, and a spring actuated locking member adapted to retain the token or indicator in the casing against the action of the levers when the key or plug is withdrawn substantially as described.

3. A lock and indicator or "locator" as set forth comprising a base or back plate with a casing or cover attached and formed

with a key or plug aperture in front and an opening in the top for the token or indicator, a carrier plate enclosed in the casing and supported on the back plate said carrier plate being formed with guide passages at right angles for the key or plug and token or indicator respectively, a pair of spring actuated levers mounted between the carrier plate and back plate and having thereon pins and projections in the paths of both the key or plug and token or indicator, and means controlled by the key or plug for retaining the token or indicator in the casing against the action of the levers substantially as described.

In testimony whereof he has affixed his signature.

EDWARD ALARIC FALCONER.
